No. 893,716.

PATENTED JULY 21, 1908.

J. H. GAVIN.
LAVATORY.
APPLICATION FILED FEB. 24, 1906.

UNITED STATES PATENT OFFICE.

JOHN H. GAVIN, OF CHICAGO, ILLINOIS, ASSIGNOR TO L. WOLFF MANUFACTURING COMPANY, OF CHICAGO, ILLINOIS, A CORPORATION OF ILLINOIS.

LAVATORY.

No. 893,716.

Specification of Letters Patent.

Patented July 21, 1908.

Application filed February 24, 1906. Serial No. 302,758.

To all whom it may concern:

Be it known that I, JOHN H. GAVIN, a citizen of the United States, residing in Chicago, in the county of Cook and State of Illinois, 5 have invented a new and useful Improvement in Lavatories, of which the following is a specification.

My invention relates to improvements in lavatories.

10 My invention consists in the novel construction of parts and devices and in the novel combinations of parts and devices herein shown and described and more particularly specified in the claims.

15 In the accompanying drawing forming a part of this specification, Figure 1 is a plan view of a lavatory embodying my invention. Fig. 2 is a vertical section on line 2--2 of Fig. 1. Fig. 3 is a vertical section on line 3--3 of 20 Fig. 1 and Fig. 4 is a vertical section on line 4--4 of Fig. 1.

In the drawing, A represents a one piece lavatory of porcelain, earthenware or other suitable material having a bowl portion B, a 25 rim or table portion C, an integral back portion D, a depending apron E, an overflow passage F and a raised tumbler shelf or holder H extending horizontally from the upper portion of the back D and perforated 30 at the corner portion thereof if the lavatory is of the corner type. The tumbler shelf or holder H is furnished with a removable perforated disk h fitting in a circular recess h¹ of the tumbler shelf or holder H. The lavatory 35 is also provided through its upright back with a drain passage F¹ communicating with the overflow passage F so that water dripping from the tumbler or from the faucet above the tumbler may escape into the overflow 40 passage F and through it into the waste passage F² which is closed by the customary plug in the bottom wall b of the bowl B. The back wall b¹ of the bowl has near the top thereof an overflow opening b² communicating 45 with the overflow passage F. The lavatory A is further provided with a recess or depression C¹ in the table or rim C for holding soap, the same being preferably furnished with raised ribs C² with a drain passage C³ 50 communicating with the interior of the bowl. The lavatory is further provided preferably with a supply passage G, the walls g of which are integral with the lavatory. And this supply passage is preferably furnished with 55 an overhanging lip g¹ to deflect the water

against the back wall of the bowl and prevent splashing. The lavatory is further preferably provided with an opening c¹³ above the overflow passage F in the table or rim portion C to receive the lifting rod or device by which the plug or valve that closes the waste opening in the bottom of the bowl is operated.

All the different parts or walls of my lavatory are integral with each other, being 65 molded or cast in one piece. As the glass holder or shelf H is at or near the top of the back D, there is no danger of the glass tumbler being accidentally broken as is the case where a seat for its reception is provided on 70 the level of the rim of the bowl, and as my raised glass holder or shelf H is furnished with a drain passage communicating with the overflow passage and waste passage of the bowl, my improved lavatory is of a very 75 neat, clean and sanitary construction.

I claim:

1. A single piece lavatory comprising a bowl, an overflow passage for the bowl, an upright back projecting above the uppermost rim of the bowl, a tumbler holder or shelf at the upper portion of the back and a drain passage leading therefrom and communicating with the overflow passage, the walls of said drain passage and overflow passage and of the bowl and back being all integral with each other, substantially as specified.

2. A single piece lavatory comprising a bowl, an overflow passage for the bowl, an upright back projecting above the uppermost rim of the bowl, a tumbler holder or shelf at the upper portion of the back and a drain passage leading therefrom and communicating with the overflow passage, the walls of said drain passage and overflow passage and of the bowl and back being all integral with each other, said tumbler holder or shelf having a recess and provided with a perforated disk fitting in said recess, substantially as specified.

3. In a one piece corner lavatory comprising a bowl, an overflow passage extending from the upper portion of the bowl to the waste passage, an upright corner shaped back projecting above the uppermost rim of the bowl and provided at the corner thereof with a recess for holding a tumbler and a drain passage extending therefrom through the corner of the upright back and commu-

nicating with the overflow passage of the bowl, substantially as specified.

4. In a one piece corner lavatory comprising a bowl, an overflow passage extending from the upper portion of the bowl to the waste passage, an upright corner shaped back projecting above the uppermost rim of the bowl and provided at the corner thereof with a recess for holding a tumbler and a drain passage extending therefrom through the corner of the upright back and communicating with the overflow passage of the bowl, said bowl having also in its rim or table portion a soap holder depression furnished with a drain passage communicating with the bowl, substantially as specified.
5. In a one piece corner lavatory comprising a bowl, an overflow passage extending from the upper portion of the bowl to the waste passage, an upright corner shaped back projecting above the uppermost rim of the bowl and provided at the corner thereof with a recess for holding a tumbler and a

drain passage extending therefrom through the corner of the upright back and communicating with the overflow passage of the bowl, said lavatory having also a water supply passage, the walls of which are integral with the other parts, substantially as specified.

6. A sink of vitreous ware or the like, having a rim around its upper edge and a continuous imperforate flange pendent from said rim, serving to reinforce the rim and the bowl and also constituting a drip shield.

7. A sink of vitreous ware or the like, having a rim around its upper edge and a continuous imperforate flange pendent from said rim, serving to reinforce the rim and the bowl and also constituting a drip shield, the whole being formed as an integral homogeneous structure of plastic material.

JOHN H. GAVIN.
